UNITED STATES PATENT OFFICE.

WILLIAM F. KERLIN, OF ROCKFIELD, AND EDWARD W. BOWEN, OF DELPHI, INDIANA.

REINFORCING DEVICE.

No. 926,005.

Specification of Letters Patent.

Patented June 22, 1909.

Application filed May 19, 1908. Serial No. 433,774.

To all whom it may concern:

Be it known that we, WILLIAM F. KERLIN and EDWARD W. BOWEN, citizens of the United States, residing at Rockfield and Delphi, in the county of Carroll and State of Indiana, have invented certain new and useful Improvements in Reinforcing Devices; and we do hereby declare the following to be a full, clear, and exact description of the invention, such as will enable others skilled in the art to which it appertains to make and use the same.

This invention relates to new and useful improvements in reinforcements for plastic material when molded in various shapes.

It is an object of the invention to provide a novel device of this character employing a reinforce consisting of a sheet of metal provided with blades or flaps extending in various directions in order to assure a greater reinforcement to a smaller quantity of material without dividing the material by large areas of metal.

It is also an object of the invention to provide a novel reinforcement for a plastic body employing a plurality of wires to strengthen the reinforce proper and enable the same to make effective resistance to any jar or pressure coming upon any part of the body when completed.

It is also an object of the invention to provide a novel reinforcement for a plastic post wherein said reinforcement projects beyond a face of the post to produce a means for the attachment of wires.

It is also an object of the invention to provide in the projected portion of the reinforcement elongated openings, each having in communication therewith a slot or slit from the outer edge of the projected portion, said elongated openings permitting the metal to be swung to one side so as to admit the lateral wires of the fence.

It is also an object of the invention to provide a novel device of this character which will be simple in construction, efficient and advantageous in practice and comparatively inexpensive to manufacture.

With the above and other objects in view the invention consists in the details of construction and in the novel arrangement and combination of parts to be hereinafter more particularly referred to.

In describing the invention in detail reference will be had to the accompanying drawings forming part of this specification, where-

in like characters of reference denote corresponding parts in the several views, and in which,

Figure 1 is a view in perspective of the reinforcement constructed according to the present invention when to be applied to posts. Fig. 2 is a view in cross section of a mold for forming a plastic post with the reinforcement embedded therein. Fig. 3 is a view in cross section of a modified form of the invention. Fig. 4 is a view in perspective of the reinforcement employed in Fig. 3, and, Fig. 5 is a view in perspective illustrating a slightly modified form of Fig. 1.

In the drawings 1 denotes a strip of metal of proper length and width having a major portion 2 projected, said major portion extending from the upper end of the strip when applied to a point below the center thereof. The remaining portion of the strip, or that portion not projected, is adapted to be embedded within that portion of the post which constitutes the base thereof. At predetermined intervals the opposite portion of the strip 1 is slotted to form blades 3, said blades having their ends bent upon themselves to form eyes or sleeves 4. The blades 3 are arranged in succession one angular with relation to the other, and it is preferred that they be bent or positioned as shown in the drawings wherein one blade is in the same plane with the body 1, while the next blade is bent to one side thereof upon a suitable angle, while the next blade is in the same plane with the first named blade. The next blade is bent in a direction opposite to that of the second named blade on approximately the same degree of angle. This arrangement continues the entire length of the body 1, and it has been found best that the blades be of such width as to permit a straight blade to be located at both ends of the strip.

In order to permit the reinforcement to give additional strength to the post or other body formed of plastic material, when applied, there are passed through the eyes or sleeves 4 of the blades the wires 5, which may be secured thereto in any desired manner, but preferably by brazing. By the use of these wires the post is very materially strengthened, as it permits effective resistance to any jar or pressure coming upon any part of the post, as is believed to be apparent. The wires secured to the center or straight blades will withstand any pressure or jar on the rear of the post, while the wires secured to the

side blades will withstand any pressure or jar on the sides of the post. The reinforcement is further provided with the wires 6 which are positioned to either side of the straight blades 3, and interposed between said straight blades and the side blades in proximity to the junction of the side blades with the body 1. These wires 6 are also brazed to the various blades 3 with which they contact. By 10 the employment of these wires 6 the reinforcement is greatly strengthened the entire length thereof, but more especially, when applied to the post, at the break of the post or ground line when the post is set.

15 It is believed well to state that the wires 5 and 6 extend the entire length of the body 1, but it has been desired that certain of the wires 5 and 6 be projected above the top of the body 1, and that these projected portions 20 be formed into eyes 7 which are intended to extend above the post when completed to provide means for securing top wires, preferably barbed wire.

The projected portion 2 of the body 1 is 25 intended to project beyond a face of the post to which the reinforcement is applied. This projected portion is provided with a plurality of suitably spaced elongated openings 8 arranged longitudinally of the projected portion. The upper edge of each of the openings 8 is a continuation of a downwardly inclined slit 9. These elongated openings are 30 for the retention of the wires forming part of the fence and by having the slit extended 35 from the outer edge of the projected portion 2 above the openings 8 the slit does not in any way decrease the strength of the metal immediately in front of the opening 8. By having the opening 8 elongated, the metal 40 can be sprung to one side so as to admit the lateral wires of the fence which can be readily pressed into said openings. The slits 9 being above the respective openings and cut to the rear edge and above the openings prevents 45 the wires when in the openings from being forced out through the slits, a feature which in the practical use of the post is found most essential.

In Fig. 3 is shown a cross section of a 50 slightly modified form of post, such post as is intended to be employed as a telegraph pole, or the like. In this instance the body 10, of suitable metal is slit at intervals along its opposed longitudinal edge to form blades 11 which are bent in a manner similar to that disclosed in Fig. 1. This reinforcement is 55 also provided with reinforcing wires 12 and 13, arranged similar to the wires 5 and 6 (hereinbefore referred to), respectively.

60 In Fig. 5 is disclosed a form of reinforcement somewhat similar to that in Fig. 1, except that there is a straight blade 14, a blade 15 bent angularly to the left thereof, and then a blade 16 bent angularly to the right 65 thereof when the succeeding blades then con-

tinue downwardly in succession in a similar manner. In other respects the invention is the same in every way.

Part of the subject matter broadly covered by the appended claims is not specifically 70 claimed herein, but forms the subject matter of a separate application filed by us on April 27, 1909, Ser. No. 492,573.

What we claim is:

1. A metallic reinforcement for plastic material, comprising a flat body portion having one of its edges slitted at pre-determined distances throughout its length to form blades, each alternate blade remaining in alinement with the face of the body and each intermediary blade extending at an angle to the face of the body and disposed alternately at opposite sides of the body, said blades having wire-engaging means thereon. 75

2. A metallic reinforcement for plastic material, comprising a flat body portion having one of its edges slitted at pre-determined distances throughout its length to form blades, each alternate blade remaining in alinement with the face of the body and each intermediary blade extending at an angle to the face of the body and disposed alternately at opposite sides of the body, said blades having sleeves at their outer ends, wires extended through said sleeves and a wire at each side 80 of the blades extending in alinement with the face of the body and between the angular blades and straight blades. 90

3. A metallic reinforcement for plastic material, comprising a flat body portion having one of its edges slitted at pre-determined distances throughout its length to form blades, each alternate blade remaining in alinement with the face of the body and each intermediary blade extending at an angle to the face 100 of the body and disposed alternately at opposite sides of the body, said body portion having a projection at its edge opposite the blades in which are formed elongated openings and downwardly inclined slits extending 105 from the outer edge of the projection to the openings. 110

4. A metallic reinforcement for plastic material comprising a flat body portion having several rows of blades projecting therefrom, one row remaining in alinement with the face of the body, and other rows extending at an angle to the face of the body and disposed at opposite sides of the body, and wires or rods connecting the blades together. 115

5. A metallic reinforcement for plastic material comprising a flat body portion having several rows of blades projecting therefrom, one row remaining in alinement with the face of the body, and the other rows extending at an angle to the face of the body and disposed at opposite sides of the body, and wires or rods connecting the blades together, the said body portion having a projection at its edge opposite the first row of blades in which are 120 125 130

formed elongated openings and inclined slits extending from the outer edge of the projections to the openings.

6. A metallic reinforcement for plastic material comprising a flat body portion having a plurality of blades projecting therefrom, said blades projecting at an angle to the body portion at opposite sides thereof, and wires or rods connecting the blades together, there being one rod for each set of blades and each wire holding all the blades of its set in alignment.

7. A metallic reinforcement for plastic material, comprising a flat body portion having one of its edges slitted at pre-determined dis-

tances throughout its length to form blades, some of the blades remaining in alignment with the face of the body and other blades extending at an angle to the face of the body and disposed at opposite sides of the body, 20 said blades having wire-engaging means thereon.

In testimony whereof we have signed our names to this specification in the presence of two subscribing witnesses.
